UNITED STATES PATENT OFFICE.

MARTIN BENNETT, JR., OF HARTFORD, CONNECTICUT.

DESIGN FOR REVOLVING ENVELOPE-RACKS.

Specification forming part of Design No. 7,806, dated October 27, 1874; application filed May 25, 1874.
[Term of Patent 7 years.]

To all whom it may concern:

Be it known that I, MARTIN BENNETT, Jr., of Hartford, in the county of Hartford and State of Connecticut, have invented a Design for a Revolving Envelope-Rack, of which the following is a specification:

The nature of my design is fully represented in the accompanying photographic illustration, to which reference is made.

My invention is intended for use in insurance offices and other places where a large number of envelopes with different printed addresses are required to be readily accessible for use. The top part, which holds the

envelopes, is divided into several hundred compartments, while beneath each opening is a space. The body of the rack is a revolving cylinder, with a slightly conical top, which can be turned to any position. It is supported upon a stand.

What I claim as my invention is—

The form of the revolving cylinder and the contained subdivisions, substantially as herein described.

MARTIN BENNETT, JR.
